ROLLER BRACKET

Claud McCauley, Dallas, Tex., assignor to Clifford O. McCauley, Denver, Colo.

Application September 19, 1938, Serial No. 230,636

1 Claim. (Cl. 156—34)

This invention relates to new and useful improvements in shade operating brackets.

One object of the invention is to provide a bracket for suspending and operating sun awnings or window shades of any type, without the use of springs, catches or locks.

Another object of the invention is to provide a bracket for suspending and operating sun awnings or window shades of any type, whereby the life of said shades or awnings are increased through the use of said invention.

Another object of the invention is to provide a bracket of the character described whereby both shades and awnings may be raised or lowered, retained in adjusted position, and at all times maintain a neat and even appearance.

The invention will be more readily understood from a reading of the following specification and by reference to the accompanying drawing wherein the invention is disclosed and wherein:

Figure 1 is a perspective view of a bracket constructed in accordance with the invention and shown as applied to a sun awning.

Figure 2 is a side elevation of a sun awning attached to a house by a bracket constructed in accordance with the invention and showing the possible positions of said awning in dotted lines.

Figure 3 is a plan view of the bracket.

Figure 4 is a side elevation of the same.

Figure 5 is a transverse vertical sectional view taken on the line 5—5 of Figure 3.

Figure 6 is an isometric view of the friction retaining clip, and

Figure 7 is an isometric view of another form of the invention.

In the drawing the numeral 10 designates a window frame of the usual type now sold on the open market. Brackets 11 and 12 are suitably secured at the upper end of the frame 10 and at each end thereof.

A roller type awning 13, having the usual wooden body or cylinder 14 upon which the awning is mounted, is retained within the brackets. A suitable pipe frame 15 having one end attached to the frame 10 by camel back hinges 16 serves to retain the outer end of the awning, as shown. The lower end of the awning is secured to the outer end of the frame 15.

For propelling the roller body 14 in either a clockwise or counter-clockwise motion, thereby raising or lowering the awning a corrugated wheel 17 is provided. The wheel is provided with a cylindrical axle 18 on one side thereof. This axle 18 is retained within a slot 19 provided in the bracket 11.

A suitable cord 20 is passed over the wheel 17. A retaining clip 21 is then slipped into a vertical slot 22 provided within the side face of the bracket. This clip is so formed whereby the cord 20 is held, at all times, in intimate contact with both the wheel 17 and the clip 21.

The opposite side of the wheel is provided with a square axle 23. This axle is fitted into a complementary square bushing 24 which has been driven into one end of the body 14.

Thus it will be seen that a suitable connection is established between the propelling wheel 17 and the body 14. The other end of the body 14 is provided with a pin 25 which is fitted into a slot 26 provided in the bracket 12. This pin allows a free clockwise or counter-clockwise movement at that end of the body 14 while the axle 18 and slot 19 of the wheel 17 and bracket 11 respectively, accomplish the same purpose at the other end of the body.

In operation, it may be seen that the awning may be raised or lowered, as may be desired, merely by imparting motion to the wheel 17. As will be seen, the cord 20 accomplishes this with the help of the friction clip 21. One end of the cord 20 may be lowered thus imparting a clockwise motion to the body 14 thereby raising the awning 13. By lowering the other end of the cord 20 a counter-clockwise motion is produced whereby the awning may be lowered.

The rounded portions 29 of the clip 21 (Figure 6) are so constructed as to frictionally engage the cord 20 with sufficient pressure to prevent uncontrolled movement of the wheel 17.

In Figure 7 a slightly modified form of the invention is shown. In this the invention may be applied to common window shade rollers now on sale on the open market. In this form a corrugated wheel 30, a friction clip 31, a bracket 32 and a cord 33 are provided. The above parts are identical to the parts shown in Figures 1-6, with the exception of the wheel 30.

The wheel 30 is provided on one side with a cylindrical axle (not shown) identical to the axle 18, while on the other side of the wheel a rectangular axle 34 is provided. This axle is similar to the axle 23 described in the first form, but having a slot 35 in its outer end. A suitable sleeve 36 is engaged over the axle 34.

This slot is provided whereby the stud 37 of the usual window shade roller 38, may be inserted therein. It is to be noted that before the stud 37 is inserted within the slot 35, the spring (not shown) of the shade roller 38 is first wound to its extreme and fastened in this position. By 55

increasing the tension of the spring and then locking the same, it will be seen that a connection equal to that shown in the first form may be had.

5 From the foregoing it will be seen that a bracket suitable for use either without side awnings or inside shades may be had. The advantage of the invention with the use of awnings may readily be noted. The invention may enable the awning 10 to be raised or lowered and set in an exact position in a minimum amount of time without the aid of hooks or locks of any kind.

In use with a window shade the advantages are even greater. The shade need never be 15 touched thereby eliminating the dirt and tearing of said shade. Also there will at no time be an unevenness of the shade as an even pressure is applied throughout the width of the shade, and also the shade is at all times under 20 complete control, thereby eliminating runaway shades.

Manifestly, the construction as shown and de-

scribed is capable of some modification and such modification as may be construed within the scope and meaning of the appended claim is also considered to be within the spirit and intent of the invention.

What is claimed is:

A shade roller bracket comprising a substantially L-shaped member having apertures in one leg and a slot and hole in the other leg, spaced from each other and from one end thereof, a 10 peripherally corrugated wheel having a spindle journaled in said hole and provided on its opposite face with a protuberance for engaging with the end of a shade roller to effect rotation of the latter when said wheel is rotated, a cord 15 overriding said wheel having free pull ends to effect rotation of said wheel and a substantially U-shaped clip retained in the slot of said L-shaped member and whose ends conformably embrace the portion of said cord overlying said 20 wheel.

CLAUD McCUALEY.
